5 Claims. (Cl. 66—24)

This invention relates to circular knitting machines provided with pattern means.

In known circular knitting machines provided with pattern means, for the production of patterned ware with stitch transfer, as well as of automatic changing-over from 1:1 rib to 2:2 rib, the drivers to be selected for the latter purpose are moved into engagement with a working cam part by effecting a vertical and a simultaneous radial movement, the cusp of said part being situated above the point of transition over to said part for the height of the driver heel at least. By this means, direct changing-over from a needle to the next one is intended to be obtained within the range of the selective 10 needle divisions.

With machines of small diameter that are provided with fine needle divisions the above-mentioned arrangement does not warrant sufficient reliability of operation for the reason that the time allowed for connecting and disconnecting the working cam part concerned is too short. In consequence thereof ruptures of needle drivers and needles are liable to arise. Apart from this, said arrangement requires at least two needle or driver heel guide grooves per lock plate as well as extra lock part for depressing the needle drivers into the cylinder grooves or the rib disc grooves. The simultaneous vertical and radial movements of the drivers associated with fine needle divisions subject the driver heels and the cylinder or rib disc tongues between adjacent grooves to bending strains to such an extent that the perfect run of the machine is impaired.

According to this invention, in a circular knitting machine provided with pattern means for the production of patterned ware, and particularly with automatic change-over means from 1:1 rib to 2:2 rib, these drawbacks are eliminated in that at least two groups of needles or needle drivers, respectively, of different shank construction are arranged circumferentially of the machine, and an equal number of movable lock cam parts are provided each of which cooperates only with one of the various needle groups and is adapted to be adjusted while positioned beyond the range of its associated needle group.

Advantageously, the surface of the rib disc and/or that of the cylinder facing towards the lock parts as well as the shank sides of the needles or drivers facing towards said parts are provided with at least one setback.

An embodiment of the invention, representing a pattern device in combination with a circular

knitting machine adapted for effecting transfer of stitches, is illustrated in partly schematic fashion, however, only to an extent required for a good understanding of the invention, in the accompanying drawing in which

Fig. 1 is a section through the needle cylinder and the rib dial of a circular knitting machine;

Figs. 2 and 2a depict a top plan view of Fig. 1 with the dial plate removed and with the rib dial lock exposed so as to show the rib disc in two different positions that are offset 180° relatively to each other;

Figs. 3 and 3a each represent an elevation of the cylinder lock as seen in the direction of arrow A in Fig. 1 with the cylinder shell removed and the cylinder shown to be in two different positions offset 180° relatively to each other, and

Fig. 4 is a view of a detail of Fig. 1 on a larger scale.

20 The numeral 1 refers to the cylinder shell including lock parts 2 to 5 contained in a first lock system and lock parts 2' to 5' contained in a second lock system, whereas 6 designates the dial plate comprising lock cam parts 7 to 9 contained in a first lock system and lock cam parts 7' to 9' contained in a second lock system.

In the needle cylinder 10 associated needle drivers 12, 13 and 12', 14' respectively are mounted and coupled to needles 11 so as to be selective by pattern bands 24 or 24' respectively, in a known manner.

By this means, the projecting driver heels 12', 13' and 14', that is, those driver heels not having been pushed back by the pattern band, get 35 within the embrace of the lock cam parts 2 and 2' respectively, thereby being raised, whereas the other drivers remain below. The rising drivers shift the needles 11 coupled therewith upward so that they can operate or transfer the stitch with which they are engaged to the oppositely disposed needles, while the needles not having been raised remain out of operation. The selecting of the drivers 12, 14, 13, that is, of the respective needles 11 by the pattern band is effected, for example, for the purpose of producing open patterned ware by transfer of stitches.

If, however, one and the same piece of ware is to be provided with knitting produced by other methods, for example, 1:1 rib or the like, that is, knitting without transfer of stitches and patterning or, if by means of transfer of stitches automatic change-over from 1:1 rib either to 2:2 rib or plain is required, additional needle selecting positions must be provided apart from the needle

selecting positions provided by the pattern band for the patterned portion.

These additional selecting positions are obtained by further lock parts 4, 5 and 4', 5' respectively as well as by needle and driver groups of different shank constructions. With a view to avoiding the necessity of providing further needle grooves or grooves for the driver heels and consequently reducing the height of the cylinder to a minimum the surfaces of the cylinder and of the drivers facing towards the lock parts are provided with one setback at least. These setbacks are designated by 15 and 16 for the cylinder and the drivers 14 respectively.

Thus, for example, for producing a change-over from 1:1 rib to 2:2 rib each third needle on one circumferential half of the cylinder is provided with a driver 13 and on the other half with a driver 14. In the present instance two driver groups 13 and 14 are provided apart from the normal drivers 12 and also two relatively oppositely disposed lock systems comprising lock parts 2 to 5 and 2' to 5' respectively.

If then in changing over from 1:1 rib to 2:2 rib it is required to effect a stitch transfer with each third needle this is carried out as follows:

The lock parts 4 (Fig. 2) and 4' respectively are moved into position of operation whereby the entirety of driver heels is displaced into oblique position of inoperation, that is, beyond the embrace of the pattern band 24 (Fig. 1) and 24' respectively.

Further the lock parts 5 and 5' respectively are moved into position of operation in the direction of arrow B in Fig. 1, namely, lock part 5, when this part is positioned opposite to the drivers 14, and lock part 5', when this part is positioned opposite to the drivers 13. By this means the drivers are not influenced while being in position out of operation, but are influenced just while the drivers 13 pass across the lock part 5 and the drivers 14 across the lock part 5'. The drivers 13 and 14 are thus erected into position for operation, that is, moved from the oblique into vertical position and pushed upward by the lock cam portions 2 and 2' respectively for transferring the stitches carried thereby to the respective opposed needles without performing any floating motion. The returning of the lock parts 5 or 5' respectively into ineffective position is carried out as these parts are juxtaposed to the drivers 14 or 13 by which means any floating motion of the drivers from their positions is avoided.

The device described above can be combined also with the rib dial lock 6.20 in that as shown in Figs. 2 and 2a by the movable lock parts 9 or 9' the needles 18 or 19 respectively are selectively moved into engagement with the lock parts 7 or 7' in a manner similar to that in which the lock parts 5 and 5' cooperate with the drivers 13 and 14 respectively to the same effect.

For this purpose the dial plate 20 is provided with a setback 21 and the needles 19 each carry a setback 22. The needles 17, 18 and 19 can be moved according to a pattern into engagement with the lock parts 7 and 7' with the aid of a conventional pattern wheel 23 instead of by means of the lock parts 9 and 9'.

The range of variability of patterning of the machine can be increased if the surface of the dial plate 20 or that of the cylinder 10 facing towards the lock parts as well as the shank sides of the needles or of the drivers facing towards the lock parts are provided with several setbacks

and a corresponding number of movable lock portions are used.

I claim:

1. In a circular knitting machine provided with pattern means, particularly for producing automatic changing-over from 1:1 rib to 2:2 rib, a needle cylinder displaceably carrying circumferentially thereof two groups of needles in addition to the normal needles, shank like means associated with each of said additional needles for the latter to be driven through said means, the shanks of said means being differently configurated for each of said needle groups, two movable lock portions each for cooperation with only one of said needle groups, and means for adjusting each of said movable lock portions while the respective lock portion is situated beyond the embrace of the correlated needle group.
2. In a circular knitting machine provided with pattern means, particularly for producing automatic changing-over from 1:1 rib to 2:2 rib, a needle cylinder displaceably carrying circumferentially thereof at least two groups of needles in addition to the normal needles, shank like means associated with each of said additional needles for the latter to be driven through said means, the shanks of said means being differently configurated for each of said needle groups, movable lock portions provided in a number equal to the number of needle groups installed, each of said lock portions for cooperation with only one of said needle groups, and means for adjusting each of said movable lock portions while the respective lock portion is situated beyond the embrace of the correlated needle group.
3. In a circular knitting machine provided with pattern means, particularly for producing automatic changing-over from 1:1 rib to 2:2 rib, a rib dial displaceably carrying radially thereof two groups of needles in addition to the normal needles, shank like means associated with each of said additional needles for the latter to be driven through said means, the shanks of said means being differently configurated for each of said needle groups, two movable lock portions each for cooperation with only one of said needle groups, the surface portions of said rib dial as well as those of said shanks facing towards said lock portions being provided with corresponding setbacks, and means for adjusting each of said movable lock portions while the respective lock portion is situated beyond the embrace of the correlated needle group.
4. In a circular knitting machine provided with pattern means, particularly for producing automatic changing-over from 1:1 rib to 2:2 rib, a rib dial displaceably carrying radially thereof at least two groups of needles in addition to the normal needles, shank like means associated with each of said additional needles for the latter to be driven through said means, the shanks of said means being differently configurated for each of said needle groups, movable lock portions provided in a number equal to the number of needle groups installed, each of said lock portions for cooperation with only one of said needle groups, the surface portions of said rib dial as well as those of said shanks facing towards said lock portions being provided with corresponding setbacks, and means for adjusting each of said movable lock portions while the respective lock portion is situated beyond the embrace of the correlated needle group.
5. In a circular knitting machine provided with pattern means, particularly for producing auto-

matic changing-over from 1:1 rib to 2:2 rib, a needle cylinder displaceably carrying circumferentially thereof at least two groups of needles in addition to the normal needles, a rib dial displaceably carrying radially thereof at least two groups of needles in addition to the normal dial needles, shank like means associated with each of said additional needles for the latter to be driven through said means, the shanks of said means being differently configurated for each pair 10 of cooperative needle groups, movable lock por-

5 tions provided in said cylinder and in said rib dial for each of said parts in a number equal to the number of needle groups installed in the respective said part, each of said lock portions for cooperation with only one of said needle groups, and means for adjusting each of said movable lock portions while the respective lock portion is situated beyond the embrace of the correlated needle group.

HANS DIEM.
